TYPEWRITING MACHINE

Ronald D. Dodge, Rochester, N. Y., assignor to
International Business Machines Corporation,
New York, N. Y., a corporation of New York

Application June 15, 1937, Serial No. 148,270

9 Claims. (Cl. 197—84)

This invention relates to typewriting machines.

The broad object of the present invention is to provide an improved spacing mechanism for the carriages of typewriting machines.

An object is to provide an improved spacing mechanism which varies the spacing of the characters to correspond with their widths.

Another object is to provide a spacing mechanism in which means are provided to vary the spacing of the carriage in accordance with the widths of the upper case letters as well as the lower case letters.

An object is to provide means whereby justification of typewritten copy may be accomplished.

An object is to provide a novel indicating device for effecting justification of typewritten lines.

Further objects of the instant invention reside in any novel feature of construction or operation or novel combination of parts present in the embodiment of the invention described and shown in the accompanying drawings whether within or without the scope of the appended claims and irrespective of other specific statements as to the scope of the invention contained herein.

In the drawings:

Fig. 1 is a vertical section of a power operated typewriter embodying the present invention;

Fig. 2 is a horizontal section on the line 2—2 in Fig. 1;

Fig. 3 is a large scale plan view of the escapement mechanism;

Fig. 4 is a large scale vertical section showing the escapement mechanism partly in section and showing the escapement selecting mechanism;

Fig. 5 is a vertical section on the line 5—5 in Fig. 4;

Fig. 6 is an enlarged side elevation of the right hand end of the carriage;

Fig. 7 is a vertical section on the line 7—7 in Fig. 4;

Fig. 8 is a rear elevation showing the tabulating mechanism in operated position;

Fig. 9 is a plan view of the justification indicator mechanism;

Fig. 10 is a detail view of a portion of the mechanism for operating the justification indicator;

Figs. 11 and 12 are diagrammatic views of the front paper guide and aligning scale;

Fig. 13 is a side elevation of the tabulator key;

Fig. 14 is a large scale detail view of part of the carriage release mechanism;

Fig. 15 is a section on the line 15—15 in Fig. 14.

The drawings illustrate the present invention as applied to the "International" electric writing machine formerly known as the "Electromatic". 5 However, it will be understood the invention is not limited in application to the specific machine selected for purposes of illustration but may be applied to other typewriters, whether manually or power operated. Since the "International" 10 electric writing machine is now well known in the art and fully described in patents covering the various mechanisms comprising this machine, only a very brief general description will 15 be given of the machine such as will enable the present invention to be understood.

The numeral 10 in Fig. 1 designates the usual character keys on key levers 11 pivoted on a rod 12 which is supported by a cross frame 13 rigidly mounted in the base 14. Rotatably mounted in the base 14 is the power roller 15 which is rotated in the direction of the arrow (Fig. 1) by means of a motor, not shown, by means of a worm drive 17 (Fig. 2), the worm shaft 17a in Fig. 2 being connected to the motor by means of a suitable flexible connection. When the machine is in use the power roller 15 rotates continually.

Cooperating with the power roller 15 are the cam units 16 which are pivotally mounted on rods 17 extending parallel with the power roller 15. There is a cam unit 16 associated with each of the key levers 11 and each cam unit is connected by a link 18 with a sub-lever 19 pivoted on rod 12. The sub-levers 19 are connected by links 20 to type bars 21 through the medium of toggles 22. The type bars 21 are pivoted in the usual wire segment 23 provided with a type guide 24 located in front of the platen 25. The platen is as usual rotatably mounted in the carriage 26 which is supported on front and rear rails 27 and 28, respectively, by means of suitable anti-friction roller trucks. Springs 29 connected to a curved spring anchoring member 30 and to toggles 22 provide means for locking the toggles 45 in the normal position shown in Fig. 1.

When any character key 10 is depressed, its cam unit 16 is caused to operatively engage the power roller 15 in a well known way thereby rocking the cam unit 16 clockwise or counter-clockwise according to whether the operative cam unit is pivoted on the left hand or right hand rod 17, respectively. The rocking of the cam unit causes its link 18 to be drawn downwardly, thereby rocking the corresponding sub-lever 19 in a 55

clockwise direction. This movement of the sublever 19, through the corresponding link 20 and toggle 22, causes the type bar associated with the selected key to rock in a counterclockwise direction to effect the impression of the type upon a work sheet wrapped around the platen 25. The type bar, near the end of its operative stroke, engages the usual universal bar 31 and causes the universal bar to move rearwardly and 10 downwardly in Fig. 1.

The segment 23 is mounted in a frame 32 which forms part of the type basket. The type basket is movably mounted in the framework of the machine for case shifting movement in a well known way and normally occupies an elevated position shown in Fig. 1 for the typing of the lower case characters. The shift mechanism for drawing the type basket 32 downwardly to permit the printing of capital letters is described in 15 Patent No. 1,945,097 and is partly shown in Fig. 4.

Secured to the back of the type basket frame 32 is a pair of brackets like 33 connected by toggle links 34 to the arms of toggle levers 35 secured on the ends of a shaft 36 journaled in the framework of the machine. Pivoted on the stud 37 is a three-armed lever 38 having two pins 38a, 38b engageable by the short arms of a T-shaped lever 39 which is pivotally mounted at 40 on one 30 arm of a three-armed lever 41. The lever 38 is connected by a link 42 to one arm of the toggle lever 35. The T lever 39 has a stud 43 projecting into a slot formed in an arm 44 comprising an extension of the shift key lever. One arm of lever 41 has a link connection 45 to a cam unit, not shown, which is controlled by a shift key, also not shown.

When the shift key is depressed the T lever 39 is elevated to bring one of the short arms thereof 40 to a position to the left of the pin 38a, this movement taking place before the cam unit controlled by the shift key is operatively connected to the power roller 15. When the cam unit controlled by the shift key is operated, the link 45 is drawn 45 downwardly thereby rocking lever 41 in a clockwise direction. This draws the T-lever 39 to the right in Fig. 4, thereby, through the engagement of said T-lever with the pin 38a, rocking the lever 38 clockwise. Through the link connection 42, the toggle levers 35 and shaft 36 are rocked in a counterclockwise direction, thereby bending the toggles comprising the links 34 and the arms of levers 35, causing the type basket to be drawn downwardly.

55 The mechanism briefly described above is old and well known in the art.

The escapement mechanism is mounted in a frame casting 46 which is secured to the undersides of the front and rear rails 27, 28 (Figs. 1, 3, 60 and 4). The frame 46 is formed with two parallel struts 46a (see Fig. 3) which support the escapement ratchets which are designated 48, 49, and 50. Sleeves like 51 are loose in aligned holes in the struts 46a and support the rod 52 on which 65 the ratchets 48, 49, and 50 are rotatably mounted.

Abutting the end of each sleeve 51 is a thrust washer 53 (Fig. 3) alongside of which are located balls 54 of a combination axial and radial thrust bearing of which the outer ball race 55a is integral with a spiral pinion 55 secured to a ratchet 56.

The pinion 56 meshes constantly with a spiral rack 57 which is secured to the underside of the carriage 26.

The rear end of the pinion 55 is formed as a ball race (see Fig. 15) in cooperation with balls

58 whereby the pinion 55 and ratchet 56 rotate on the rod 52. The latter is relatively fixed in the framework by means of a set screw 59 (Fig. 3) which projects through a slot in the rear sleeve 51. A similar thrust washer like 53 abuts the 5 end of the rear sleeve 51 to retain balls which suitably mount one end of the hub of ratchet 48 for rotation on the rod 52.

The hub of ratchet 48 is integral with a pinion 60 located adjacent the hub of the ratchet 49. The pinion 60 meshes with one of a pair of intermeshing pinions 61 rotatably mounted on brackets 62 carried by the ratchet wheel 49 while the other pinion 61 meshes with a pinion 63 which is secured to a pinion 64. The pinion 64 meshes 15 with one of a similar pair of intermeshing pinions 65 mounted on brackets 66 carried by ratchet wheel 50, while the other pinion 65 meshes with a pinion 67.

Rotatably mounted on the pinion 67 is a ratchet wheel 68 (Figs. 3 and 15) which is of the same diameter as the ratchet 56 while secured to the pinion 67 is a ratchet 69 which is considerably larger in diameter than the ratchets 56, 68. The ratchets 56 and 69 are normally connected 25 for driving purposes by means best shown in Figs. 14 and 15 comprising a dog 70 pivoted on a stud 71 fixedly mounted on the ratchet wheel 69. The dog 70 normally engages the teeth of the ratchet wheel 56 whereby the ratchet wheel 69 will be 30 rotated in a counterclockwise direction (Fig. 14) whenever the ratchet wheel 56 is similarly rotated by movement of the carriage. The dog 70 is slotted to embrace a stud 72 carried by a member 73 also pivotally mounted on the stud 71. 35 The member 73 has a lug engaging a stud 74 secured to the side of ratchet wheel 68. A torsion spring 75, hooked over the end of stud 74 and lying in a groove formed in a collar 76 on the pinion 67 and also anchored to a stud 77 (Fig. 7) 40 on ratchet 69, normally tends to rotate the ratchet 68 in a counterclockwise direction (Fig. 14) or in a clockwise direction (Fig. 7). A spring 75a, anchored to studs 72 and 77, holds the tooth in dog 70 in engagement with the teeth of ratchet 45 56.

Movement of the carriage is effected, as usual in typewriting machines, by means of a spring drum 78 partly shown in Fig. 3 and shown in dotted lines in Fig. 6 on which drum is wound the 50 tape 79 passing over a pulley 80 mounted on the rear rail 28 and thence to the right hand end of the rack 57 at which point the tape 79 is secured to the rack. Due to the constant tension produced in the tape 79 by the spring drum 78, the 55 carriage 26 tends to move to the left. Thus the ratchet 56 tends to rotate the ratchet 69 and pinion 67 in a counterclockwise direction (Fig. 14) or clockwise in Fig. 7. This rotational tendency of the pinion 67 is communicated to the ratchet 60 wheels 48, 49, and 50 (Fig. 3) through the train of connections comprising the pinions 60, 61, 63, 64, 65. Normally, however, this rotational tendency has no effect so far as movement of the carriage is concerned because the ratchet wheels 65 48, 49, and 50 are restrained from rotation by means of the loose dogs 81 (Fig. 5) of the escapement mechanism.

Reverse rotation of the ratchet 69 and pinion 67 is prevented by means of a dog 82 (Fig. 7) 70 pivoted on a stud 83 carried by a plate 84 which is adjustably secured to the rear rail 28. Also pivoted on stud 83 is a bracket 85 having a bumper 85a composed of resilient material such as leather against which the dog 82 is normally 75

held by a spring 86. The bracket 85 is adjustably rotated on the stud 83 until the free end of said dog 82 engages one wall of a tooth in the ratchet 69 but does not quite touch the other wall of the adjacent tooth, the object being to silence the clicking noise which ordinarily is experienced with similar ratchet-and-pawl mechanisms due to the end of the dog striking the side of the next succeeding tooth after riding over a given tooth.

It is desirable to be able to release the escapement mechanism from the carriage for the purpose of moving the carriage by hand, or when the carriage is to be returned by the usual power operated carriage return mechanism. For this purpose, there is provided release mechanism which is operated by the usual carriage release levers 87 one of which is shown in Fig. 6, these levers being pivoted on studs 87a on the side plates of the carriage with the free ends of levers 87 adjacent the usual platen rotating knobs 88. Each lever 87 abuts one end of a bail 89 pivotally mounted in the side plates of the carriage. When either of the levers 87 is depressed, the bail 89 is rocked clockwise in Fig. 6 thereby causing the rod 89 (Fig. 7), which forms part of the bail to move rearwardly of the platen or forwardly in Fig. 7. A lug 90 formed in a lever 91 (Figs. 1, 6, and 7) pivoted on the top surface of the rear rail 28 is thereby moved rearwardly of the platen, or forwardly in Fig. 7 whenever the bail 89 is moved by the release levers 87.

Mounted on a bracket 92 (Fig. 7) is a release dog 93 having a slot 93a embracing a stud 94 carried by the bracket 92. A spring 95, anchored to the lower end of the dog 93 and to the bracket 92, normally holds the lower end of said dog against a stop lug 92a formed in the bracket 92, with the stud 94 at the lower left hand end of the slot 93a. In this position of the dog 93, the lower end thereof, which is in the plane of the ratchet 68, is held clear of said ratchet. Whenever the lever 91 is moved forwardly in Fig. 7 by the rod 89 as a consequence of the operation of one of the release levers 87, the dog 93 is moved to the left in Fig. 7. Due to the inclination of the slot 93a, the dog 93 is first caused to move downwardly into engagement with ratchet 68 and thereafter, by a clockwise pivotal movement of said dog on the stud 94, the ratchet 68 is moved by dog 93 in a counterclockwise direction relative to the ratchet 69 (Fig. 7) or clockwise in Fig. 14. Through the co-operation of the pin 74 on ratchet 68 with the slot in lever 55 73, and the co-operation of pin 72 with the lug on the dog 70, the latter is lifted out of engagement with the teeth of ratchet 55 thereby permitting said ratchet to be moved independently of the ratchet 69. Thus the carriage may be moved by hand or by the power operated return mechanism without disturbing the escapement mechanism interfering with the movement of the carriage.

The dog 93 is operated automatically whenever the usual power operated return mechanism operates to return the carriage prior to writing a new line. In the "International" electric writing machine, the carriage is returned by power mechanism very similar with the one described in Patent No. 1,753,450 under control of a carriage return key. This mechanism is not shown in the present case, because it is not directly involved in the operation of the invention claimed hereinafter. It will suffice to say that

when the carriage return key is depressed, a cam unit 160 (Fig. 2) controlled thereby is operative to straighten the toggle which engages the carriage return clutch and, through a chain of connections including a link 96 (Fig. 7), a bell 5 crank 98, and a link 99, rocks a three-armed lever 100 pivoted at 101 to a plate 102 secured to the rear rail 28. The bracket 92 is secured to the plate 102.

The three-armed lever 100 controls the release 10 of the carriage return clutch and, when operated as described, moves one arm of said lever 100a into the path of the left hand marginal stop 103a carried by the usual marginal stop rack 104 mounted on the carriage. Through the 15 arm 100b and a link 105, which interconnects said arm 100b with the lever 91, the dog 93 is operated to disengage the dog 70 from the ratchet 56. During a carriage return operation, the ratchet 56 rotates in a clockwise direction (Fig. 20 14) whereby, if the dog 70 were not released by the connection including 105, a clicking noise would result which is undesirable as it makes the operation of the machine rather noisy. When the carriage approaches its left hand mar- 25 ginal position, the left hand marginal stop 103a strikes a cam surface 100c in the arm 100a of lever 100 and rocks said lever 100 in a counter-clockwise direction thereby through the links 96, 99 and bell crank 98 and for connections not 30 shown disengaging the carriage return clutch, and also permitting dog 93 to become restored by spring 95 to the position shown in Fig. 7. A lug 102a formed in plate 102 is engaged by the left hand marginal stop 103a to arrest the carriage at the left hand marginal positions. This lug 102a is also engaged by the right hand marginal stop 103b (Fig. 7).

The ratchet wheels 48, 49, and 50 have teeth, 27, 36, and 21 respectively, whereby the amount 40 of feeding movement imparted to the carriage may be varied. Due to the method of interconnecting the ratchet wheels by means of intermeshing pinions, the ratchet wheels 48 and 50 rotate in a direction opposite to the ratchet 49. 45 Assuming for the moment that the ratchet wheels 48 and 49 (Fig. 3) are fixed and immovable, the pinion 64 will be locked against rotation, therefore, if ratchet wheel 50 is now permitted to rotate one tooth space, one of the pinions 65 will 50 roll around said pinion 64 and by rotating the other pinion 65 will permit the pinion 67 to rotate in the same direction as the ratchet wheel 50 but twice as much as ratchet wheel 50. Similarly, if the ratchet wheels 48 and 50 are locked and the 55 ratchet wheel 49 is permitted to move, one of the pinions 61 will roll around the pinion 60 and cause pinions 63, 64 to be rotated. The rotation of pinion 64 is communicated to pinion 67 through the intermeshing pinions 65. As in the 60 case of ratchet wheel 50, pinion 67 rotates twice as much as ratchet wheel 49. However, when the ratchet wheels 48 and 50 are held and ratchet wheel 48 rotates, the same amount of movement will be communicated from the ratchet wheel 48 65 to the ratchet wheel 67 through the pinions 61, 63, 64, 65 acting as idlers. It is possible, however, to permit the ratchet wheels 48, 49, and 50 to rotate in combinations to produce an accumulative effect upon the pinion 55 which, of course, 70 will permit the carriage to move correspondingly.

Since the ratchet wheel 48 has twenty-seven teeth, the pinion 67 and hence the pinion 55 will be rotated $\frac{1}{27}$ of a revolution whenever the ratchet wheel 48 rotates one tooth space. On the other 75

hand, since the movement of the pinion 67 is twice that of the ratchet wheel 49 and the latter has thirty-six teeth, the pinions 67 and 55 will be rotated the equivalent of $\frac{1}{18}$ of a revolution of the ratchet wheel 49. Likewise, the ratchet wheel 50 having twenty-seven teeth, pinions 67 and 55 will be rotated $\frac{2}{27}$ of a revolution of the ratchet wheel 50. Reducing these fractions to a common denominator of 54, it will be seen that the movements of pinions 67 and 55 produced by the ratchet wheels 48, 49, 50 are $\frac{2}{54}$, $\frac{3}{54}$ and $\frac{4}{54}$ of a revolution per tooth space on the respective ratchet wheels. The gearing is so designed and the spacing of the teeth on their ratchet wheels has been so selected that ratchet wheel 48 causes the carriage to move two units of spacing, ratchet wheel 49 three units of spacing and ratchet wheel 50 four units of spacing.

It is thus possible to secure 7 different spacings 20 of the carriage which, in terms to units of carriage spacing, are as follows: 2, 3, 4, 5, 6, 7, 9. Thus the spacing of the carriage can be accommodated to seven different widths of letters if necessary. The means by which the escapement wheels 48, 49, 50 are selectively controlled will be described in the following paragraphs.

The rotation of the escapement ratchet wheels 48, 49, 50 is controlled by means of three dog rocker mechanisms which are selectively controlled by power operated selecting mechanism. Figure 5 shows the dog rocker mechanism for the ratchet wheel 49. Each dog rocker mechanism includes a dog rocker plate 106 which is pivotally mounted on vertically aligned conical studs 107 screwed into threaded holes in two parallel and horizontal portions 46b of the frame 46. The conical points of the studs are seated in conical holes in lugs formed in the dog rocker plate 106. Pivoted on a stud 108 carried by the rocker plate 106 is the usual loose escapement dog 81 mentioned hereinbefore which is actuated by a spring 109 so as to be urged in a counterclockwise direction (Fig. 7). The left hand end of the dog 81 engaging one of the teeth of the ratchet 49, however, is held in the position of Fig. 5 owing to the tension of the spring drum 78 (Fig. 4) being greater than the tension of the spring 109 (Fig. 5) whereby the dog 81 is forced against a resilient stop 110a mounted on an arm 111 which is rotatably secured to the side of the rocker plate 106 by means of the stud 108. The stud 108 has a shoulder on which the dog 81 is loose to permit the arm 111 to be secured to the plate 106 without binding the dog. The upper left hand portion of the arm 111 is provided with a bent-over lug against which bears an adjusting screw 112 carried by a lug formed in the rocker plate 106. By turning the screw 112 in one direction or another, the arm 111 may be rotatably adjusted about the stud 108 as a pivot. The dog rocker plate 106 (Fig. 3) is provided with a lug 106a which is substantially in horizontal alignment with the left end of the dog 81 but does not normally engage the teeth of the ratchet wheel 49.

65 When the rocker plate 106 is rocked in a counterclockwise direction (Fig. 3), the lug 106a is moved into the tooth space occupied by the dog 81 before said dog is moved free of the ratchet wheel whereby when the dog ultimately clears 70 teeth in the ratchet 49, the ratchet wheel is permitted to rotate counterclockwise a fraction of a tooth space in Fig. 5. The spring 109 then rocks the dog 81 in a counterclockwise direction until said dog strikes a resilient stop 110b mounted on the arm 111. The stops 110a, 110b on arm 111

are so spaced that the end of dog 81 assumes a position in horizontal alignment with the next lower tooth space of ratchet wheel 49.

When the plate 106 is restored to the position of Fig. 3, the end of dog 81 is moved into the path of the next lower tooth on ratchet wheel 49 before the lug 106a clears the teeth in ratchet 49. When the lug 106a finally clears the teeth in the ratchet 49, the ratchet wheel 49 will be permitted to rotate in a counterclockwise direction (Fig. 5) the remainder of a tooth space, thereby bringing the end of dog 81 back against the resilient stop 110a. Thus, by giving the plate 106 one complete oscillation the escapement ratchet 49 is permitted to turn one full tooth space.

15 The rocker plate 106 (Fig. 5) is formed with a lug 114 which extends between two resilient stops 115a, 115b mounted on arms 116a, 116b, respectively, which arms are pivoted in scissors fashion on one of the conical studs 107. The stops 115a, 20 115b being located on opposite sides of the lug 114, adjustably limit the oscillatory movements of the plate 106 on the studs 107 as pivots.

Similar mechanism is provided for the other two ratchet wheels 48, 49 but, owing to the fact 25 that these two ratchet wheels rotate in a direction opposite to the ratchet wheel 49, the rocker plates 106 for the ratchet wheels 48, 49 are in effect inverted. Normally, the plates 106 are held by torsion springs 117 with their lugs 114 abutting 30 the stops 115a, as shown in Fig. 3, with all of the dogs 81 engaging the teeth of their respective ratchets. Springs 117 each have one end hooked through a hole on parts 46b of frame 46 and their other end engaging the stop adjusting screws 112 35 whereby all the escapement wheels 48, 49, 50 are locked against movement.

The rocker plates 106 are selectively and combinationaly operated through power mechanism controlled by the keys 10 which selecting mech- 40 anism now will be described.

Rigidly mounted on brackets 118 (Figs. 1 and 2) secured to the lower edges of the sides of the base 14 is a rod 119 which is steadied at its mid-point by extending through a slot in a bracket 45 120 (see Fig. 4 also) secured to the frame 121 which supports the case shift mechanism and the type basket by means not shown. Pivoted mounted on the rod 119 are selector bars 122 which extend forwardly and horizontally to 50 points underneath the cam units 16. There is a selector bar 122 for each cam unit 16 and its key. Since the cam units 16 are arranged in two rows on the opposite side of the power roller 15, the bars 122 are made in two lengths which alternate 55 on the rod 119, the shorter bars 122 being interspersed with the longer bars. Each of the selector bars 122 has a link connection 123 with an extension 124 formed as part of one of the side frames of the cams and release mechanism of the cam units 16. Thus, whenever a cam unit is operated in consequence of the depression of any key 10, one of the selector bars 122 (Figs. 1 and 4) is rocked in a counterclockwise direction. 65

The selector bars 122 are provided with one or more lugs like 122a, 122b, 122c * * * 122f (Fig. 4) each designed to be engageable with one of three bails which selectively control the operation of the escapement mechanism. Each bail 70 comprises a rod 125 mounted in side arms 126 (Figs. 2 and 4) which are pivotally mounted on studs 127. These studs are carried by arms 128 the hubs of which are rigidly mounted on and near the ends of a shaft 129. This shaft is rotatably

mounted on studs 130 (Fig. 2) carried by the base 14 of the machine. The lugs 122a, 122b, 122c, and so on, are so disposed along the length of the selector bars 122 that one or more of the bails including rods 125 will be rocked counterclockwise about studs 127 as a pivot (Fig. 4) whenever the bars are operated in consequence of the depression of a key 10.

The bars 122 are guided near the mid-points of the longer bars and adjacent the ends of the shorter bars by means of a comb 131 which is secured to the lower edges of the base 14. Adjacent the rod 119, the bars 122 are guided by a comb 132 which is formed with side arms 132a attached to hubs fixedly mounted on the rod 119 as best shown in Fig. 2. Pivotaly mounted on the rod 119 near the center of the machine are three arms 133, 134, 135 which extend forwardly (Fig. 2) or to the right in Fig. 4 to overlie the rods 125. The arms 134, 135 are curved at their forward ends whereby bar 134 may be operated only by the central rod 125 and the bar 135 only by the right hand rod 125. The end of the arm 133 is straight and is operated only by the left hand rod 125. It will be seen that each time one of the selector bars 122 is rocked in a counterclockwise direction (Fig. 4) one or more of the arms 133, 134, 135 will be similarly rocked about rod 119 as a pivot.

The clockwise restoring movement of the bails including the rods 125 and arms 126 is limited by means of two brackets 136, 137 (Fig. 2) secured to the inside face of the base 114. Each bracket 136, 137 extends horizontally underneath the arms 126 and is provided with a resilient facing 138 of material such as leather and each of the arms 126 is provided with a bent-over lug 126a resting on the top surface of the adjacent resilient facing 138. By the cooperation between the lugs 126a and the resilient facings 138, the rods 125 are held upwardly slightly clear of the lugs 122a whereby the clicking noise which would result if lugs 126a were to directly strike the brackets 136, 137 is silenced.

Each of the levers 133, 134, 135 (Figs. 2 and 4) extends rearwardly of the rod 119 and supports arms 139, 140, 141 which are pivoted on studs 142 carried by the arms 133, 134, 135, respectively. Each of the arms 139, 140, 141 has a bent-over lug 143 which cooperates with the upper edge of the rear end of the corresponding levers 133, 134, 135 and these lugs are normally held in contact with said levers by means of torsion springs 144 interposed between pins carried by the arms 139, 140, 141 and pins carried by the levers 133, 134, 135. The levers 133, 134, 135 are urged in a clockwise direction by means of springs 145 anchored to pins carried by said levers and ear formed in bracket 120. The arms 139, 140, 141 have link connections 146 to arms 147, 148, 149, respectively, which are pivotally mounted on the front sides of the rocker plates 106 of the several escapements. It is evident that when one or more of the levers 134, 135, 136 is rocked in a counterclockwise direction (Fig. 4), one or more of the links 146 will be drawn downwardly thereby rocking the corresponding arms 147, 148, 149 downwardly, or clockwise in Fig. 5, which shows only the arm 148 for the middle escapement mechanism.

Secured to the rear end of frame 46 (Figs. 3 and 4) is a bracket 150 having a horizontal slot into which extends a stud 151 on a bar 152. This bar at its forward end (Figs. 3 and 4) is pivotally connected to a bell crank 153 piv-

otally mounted on a bracket 153a secured to frame 46. The bell crank 153 has a link connection 154 to the movable frame including the universal bar 31. A spring 155 anchored to a pin carried by the bar 152 and to a pin carried by the bracket 150 holds the bar 152 to the retracted position shown in Fig. 4. In order to permit the bar 152 to move to the right in Fig. 4, or forwardly in Fig. 3, independently of the universal bar 31, the link 154 has a slotted connection to the universal bar frame. The bar 152 through most of its length is L-shaped in vertical section and on the top surface of the horizontal portion of said bar there is secured three screw studs 156 located in the rear of and slightly below the ends of the arms 147, 148, 149, respectively, whereby the bar 152, if operated alone, will not affect any of the arms 147, 148, 149.

With the bails comprising rods 125, 126 in the position shown in Figs. 1, 2, and 4, depression 20 of any key 10 causes the corresponding cam unit 16 to be rocked by the power roller 15 in a clockwise or counterclockwise direction, according to whether the cam unit is in the left hand or right hand row, respectively, thereby rocking 25 the corresponding bar 122 in a counterclockwise direction and at the same time operating the corresponding type bar 21. Through the intermediary of one or more of the lugs 122b, 122d, 122f, the bar 122 which corresponds to the key 30 30 depressed will be rocked in a counterclockwise direction thereby similarly rotating one or more of the bails comprising the rods 125, 126. One or more of the levers 133, 134, 135 and their corresponding arms 139, 140, 141 is drawn downwardly thereby rocking the corresponding arms 147, 148, 149 downwardly or clockwise in Fig. 5 35 bringing the operated arms into the path of movement of the studs 156, this operation taking place before the operated type bar strikes the universal bar 31. For example, the bar 122 for the "Q" key 10, shown in front in Fig. 4, has a lug 122f whereby only the lever 135 and arm 147 are operated.

When the type bar ultimately strikes the universal bar 31, the latter is moved rearwardly or to the left in Fig. 4 thereby, through the link 154 rocking the bell crank 153 clockwise. This results in the bar 152 moving forwardly (Fig. 3) or to the right in Fig. 4. Those of the arms 147, 148, 149 which have been drawn downwardly will be engaged by the corresponding studs 156 and, as a result, the rocker plates 106 connected to said arms will be rocked counterclockwise in Fig. 3.

Upon the restoration of the type bar, the bar 152 is restored by spring 155 to the position of Figs. 3 and 4, this operation taking place during the first part of the restoring movement of the type bar and is completed by the time the type bar has receded a short distance from the printing point. With continued restoring movement of the type bar, the bails comprising rods 125 and arms 126 and the operated levers and arms 133, 134, 135 and 139, 140, 141, respectively, will be restored to the position of Fig. 4 thereby restoring the operated arms 147, 148, 149 to the position shown in Fig. 5. It will thus be seen that one or more of the escapement ratchets 148, 149, 150 will be operated with the result 70 that the carriage will be permitted to move a distance depending upon the spacing of the teeth in the selected ratchets 148, 149, 150.

The description up to the present time has assumed that the type basket is in elevated posi- 75

tion to cause the lower case characters to be printed. Many of the upper case letters of the alphabet are considerably wider than the corresponding lower case letters, particularly when type faces like those used in the printing of newspapers and books is employed. Thus, the upper case L is considerably wider than the lower case letter "I." In order to take care of these differences in width between the upper and lower case characters, means is provided to shift the bails comprising the rods 125, 126 rearwardly of the machine or to the left in Figs. 1 and 4 to cause the rods 125 to register with lugs 122a, 122c, 122e on selector bars 122.

15 An arm 157 (Fig. 4) is secured to the shaft 129 and has a link connection 158 to an arm 159 secured to the shaft 36 which it will be recalled is rocked counterclockwise each time the type basket 32 is drawn downwardly to the upper case position. Whenever the type basket is shifted to the upper case position, arm 159 is rocked counterclockwise thereby, through the link 158, rocking arm 157, the shaft 129, and the arms 128 in a clockwise direction. The bails comprising arms 125 and arms 126 are thus drawn rearwardly, or to the right in Fig. 4, to re-position the rods to register with lugs 122a, 122c, 122e. In most cases the spacing of the characters is increased when the upper case characters are printed. However, this may not be invariably the case as the extreme left hand or rear row of keys (Fig. 1) often contains combinations of characters such as parentheses and numerals which may require that the spacing be reduced for the characters printed within accompanying upper case shift movement.

It is desirable to make provision for back spacing the carriage under control of the usual back-space key. In ordinary typewriters, the amount of back-space movement is the same as the spacing given each character but in the machine described herein the back-space mechanism causes the carriage to be reversely rotated only a small amount which is considerably less than the more common spacing of $\frac{1}{16}$ of an inch per letter used in most of the machines now built for general office use. The unit of spacing employed in the illustrative machine described herein for the purpose of proportioning the spacing of letters in accordance with their widths is an arbitrary unit of the order of .022", although the smallest spacing given any printed character is twice this value. In other words, the smallest spacing of the carriage which may be accomplished by the escapement mechanism herein described is .044" per character. However, for a purpose to be described hereinafter, the back-space mechanism is capable of reversally moving the carriage one unit of spacing or .022". Obviously, these figures are purely arbitrary and will depend upon the size of the type on the type bars. Thus, if smaller type were used, such as the elite size, the basic unit of spacing would obviously have to be smaller.

65 The back space key 10a (Fig. 1) as well known in the art controls a cam unit 16a (Fig. 2) which, however, has a single lobe on its cam instead of a double lobe as is the case with the cams in the cam units 16 operating the type bars. This cam unit is not shown in Fig. 1 but is connected by a link 18a to a bell crank 160 having a link connection 161 to one arm of a bell crank 162 (Fig. 7) pivoted on a stud 163 carried by the rear rail 28. The other arm of the bell crank has a link connection 164 to a bell crank 165 pivoted

on a stud 166 carried by a bracket 167 secured to the frame 46. A back space feed dog 168 actuated by a spring 169 is pivoted on the other arm of bell crank 165 and has a bent-over lug which normally is clear of the teeth in ratchet 56. Normally the upper end of the dog 168 is held in engagement with an eccentric stud 170 on bracket 167 by spring 169 which stud holds the dog 168 clear of the teeth in ratchet 68.

When the back space key 10a is depressed, the single lobe cam unit 16a controlled thereby is caused to operatively engage the power roller 15 with the result that bell crank 160 is rotated clockwise drawing link 161 to the right in Fig. 1 or rearwardly in Fig. 7 thereby, through the bell crank 98, drawing link 164 to the left. The bell crank 165 is rocked clockwise drawing the lug in dog 168 in engagement with the teeth of ratchet 56 and thereafter rotating said ratchet in a counterclockwise direction (Fig. 7) or clockwise in Fig. 14, the dog 70 merely wiping idly over the teeth in the ratchet 56.

The space bar 10b controls a cam unit 16b (Fig. 2). This cam unit, through a link like 18a, operates a lever like 160 and a link 161a (Figs. 3 and 5) connected to an arm 171 (Fig. 5) secured to a shaft 172 which is rotatably mounted in frame 41. Also secured to shaft 172 is an arm 173 (see Fig. 4 also) which extends upwardly to one side of the plane of the lever 153 and has a pin 174 extending into the plane of lever 153. A spring 175 connected to the arm 173 and to a fixed part of the framework, holds the lever 173 in the position of Fig. 4. When the space bar is depressed, its cam unit 16b causes the lever to 35 which the link 161a is connected to rotate in a clockwise direction, as in the case of lever 160 for the back space mechanism, thereby drawing link 161a toward the front of the machine in consequence of which the arm 173 is rocked counterclockwise in Fig. 4 to first bring pin 174 in engagement with lever 153 and thereafter rock said lever in a clockwise direction. This causes the bar 152 to move to the right (Fig. 4). There is a selector bar 122a (Fig. 2) associated with the space bar cam unit 16b and this selector bar operates the bail 125, 126 which controls the arm 147 causing the latter to be drawn downwardly. It will be noted in Fig. 4 that the pin 174 under normal conditions is located far enough away from the lever 153 to allow ample time for the arm 147 to be drawn downwardly into the path of a stud 156 before bar 152 moves.

One of the principal applications for a machine such as is described herein is in the field of photolithography, that is, the preparation of lithographic plates by photographing typewritten copy, the machine being used to prepare clear cut typewritten copy which is subsequently photographed on a lithographic stone or suitable sensitized plate. This plate is treated by a suitable process to make it capable of use as a printing plate. These processes require that very clear and sharp impressions be produced by the types as frequently the typewritten master sheet, as it may be called, must be enlarged and this has the effect, when an inked textile ribbon is used in the typewriter, of enlarging the ordinarily unnoticeable defects in the printed characters which are caused by the weave of the ribbon and inequalities in the inking of the ribbon. In the preparation of master sheets for the photo-offset and other photographic process, it is desirable to use a carbon paper ribbon instead of an inked textile ribbon as it has been found that

the carbon ribbon produces sharper and more solid impressions than the textile ribbon usually employed in typewriters for general office work. The carbon ribbon is usually used but once and is thrown away.

In the present machine, provision has been made for feeding a relatively narrow strip of carbon ribbon 176 which is removed from a storage roll, not shown, and lead across the machine and through the usual ribbon guide in front of the platen (see Fig. 6), to a curved guide 177 provided with guiding lugs 177a at each end thereof. The ribbon which in Fig. 6 is led diagonally downwardly from the guide 177 to a guide 178 having guide lugs 178a. The ribbon then passes between two feed rollers 179, 180 and thence diagonally downwardly over a bracket 181 which is designed to be used as a tearing knife for occasionally breaking off the ribbon after it has passed through the feed rollers 179, 178, the severed portions of the ribbon being thrown away.

The lower feed roller 180 is rotatably mounted on one end of a shaft 182 journaled on a bracket 183 secured to the side of the base 14. The upper feed roller 179 is rotatably mounted on a stud 184 mounted at the mid-point of a release lever 185 which is pivoted at 186 to a stud carried by the bracket 183. A torsion spring 187, wound around the stud 186 and hooked over the edge of the lever 185, urges said lever in a counterclockwise direction to constantly engage the roller 179 with roller 180. In order to insure that the relatively narrow ribbon 177 will remain in its proper position between the two feed rollers 179, 180, the upper feed roller 179 is flanged so as to project on each side of the ribbon and feed roller 180 and prevents the ribbon from slipping off the feed roller 180.

The shaft 182 extends through the base 14 and is journaled in a lug formed in a bracket 183a (Figs. 3 and 4) secured to the frame 46 which supports the escapement mechanism. A bevel gear 182a secured to shaft 182 meshes with a similar bevel gear 182b secured to a short shaft 182c extending at right angles to the shaft 182 and journaled in lugs formed in the frame 183a. A large gear 182d is secured to the shaft 182c and meshes with pinion 67. In consequence of the train of gearing just described, the shaft 182 is rotated in a counterclockwise direction when the escapement mechanism is operative whereby the carbon ribbon 176 will be fed an extent depending upon the width of the character typed. However, when the carriage is released from the escapement mechanism as is the case when the carriage is tabulated by hand or returned by power, the carbon ribbon will not be fed owing to the fact that the pinion 67 is disconnected from the carriage by the operation of the carriage release mechanism shown in Figs. 14 and 15. Thus waste of the ribbon is eliminated.

It is desirable to provide tabulating mechanism to facilitate the typing of data in tabular form. Owing to the fact that the spacing mechanism causes the carriage to move variable extents commensurate with the width of the character typed and is based upon considerably smaller units of spacing than is usual in machines designed for general office use, the ordinary type of typewriter tabulator is not practical and would not operate reliably owing to the difficulties which would be experienced in attempting to use a tabular rack with tooth spacings of a size commensurate with the unit of

spacing. One reason why the usual tabulating mechanism would not operate satisfactorily is that it is usually necessary to provide rebound traps for preventing rebound of the carriage when the column stops strike the tabular stop, 5 as is well known in the art. These rebound traps operate satisfactorily for the relatively coarse spacing of the teeth on the tabular rack used in general correspondence machines which is seldom smaller than $\frac{1}{8}$ of an inch but would 10 not be practical with a tabular rack having tooth spaces as small as .022" as sufficient time would not be allowed for the rebound trap to take effect.

The tabulating mechanism is shown in Figs. 15 8 and 13. The usual marginal release key 188 of the "International" electric writing machine is herein employed to operate the tabular stop lever. This key (Fig. 13) is slidably mounted in brackets 189, 190 and its rear or left hand end 20 (Fig. 13) abuts a lug formed in one arm of a bell crank 191 which bell crank is urged in a clockwise direction (Fig. 13) by a spring 192 anchored to the bracket 190. A pin 193 is carried by the key 188 to limit the restoring movement of said key. The other arm of the bell crank 191 has a hole into which projects the narrowed portion 194a of the tabular lever 194 which is pivoted on a stud 195 (Fig. 8) carried by a bracket 196 secured to the rear rail 28. 30 Also pivoted on the stud 195 is a tabular stop arm 197 having its right hand end turned upwardly at 197a into the path of the column stop 198 on column stop rack 199. The lever 194 has a pin 200 projecting through a slot 35 formed in the lever 197 which pin is interconnected by a spring 201 with a pin 197b carried by the lever 197. The bell crank 191 (Figs. 8 and 13) is mounted on a bracket 202 secured to the rear rail 28 which bracket has a stud 203 40 screwed therein having an eccentric shoulder 203a in the plane of the bell crank 191. Shoulder 203a acts as an adjustable stop to limit clockwise movement of bell crank 191 when the key 188 is pushed to the left in Fig. 13. 45

When it is desired to tabulate the carriage, the key 188 is pushed to the left (Fig. 13) thereby rocking the bell crank 191 in a clockwise direction against the tension of spring 192. This causes the right hand end (Fig. 8) of the lever 194 to be elevated to bring the upper portion 197a into the path of the column stop 198 carried by the bar 199 as in Fig. 13. With the parts operated by the key 188 being held in this position, one of the carriage release levers 87 (Fig. 6) is depressed to disengage the carriage from the escapement mechanism and the carriage is allowed to move to the right (Fig. 8) until the stop arm 197 wipes past the desired column stop 198 and snaps to the position shown in Fig. 13. 60 The carriage release lever 87 is then released and while still holding the key 188 in its operated position, the carriage is moved by hand counter to letter spacing direction until the column stop 198 strikes the end of the stop arm 197. Thereafter the key 188 is released. 65

In order to facilitate the correction of errors in typing which has always been a problem in typewriters employing escapement mechanisms which vary the feed of the carriage in accordance with the widths of the letters typed, there is provided means whereby the carriage may be brought to a position to type the correction after erasing the erroneous character. In Figs. 11 and 12 is shown parts of the usual front pa- 75

per guide 204 which is located at the printing point on each side of the type guide for the purpose of keeping the type from fouling or embossing the paper as would happen if the paper should bulge away from the platen. A portion of the paper guide is cut away at 204a to provide a vertical straight edge for the purpose of positioning the carriage after an error has been erased. When an error is committed in typing a letter, the letter is erased and after erasure the carriage is moved by hand to position the right hand side of the next adjacent letter on the left in alignment with the straight portion 204a as shown in Fig. 11, which illustrates the use of the letter "X" to realign the carriage after erasure. Thereafter, the space bar is operated four times which causes the carriage to space sufficiently far to the left to bring the letter used for a basis for realigning the carriage to the position of Fig. 12. Thereafter, depression of the proper key to correct the error will cause the correct letter to appear in its proper position to the right of the letter used as a basis for alignment and such letter will be typed with the proper spacing.

In Figs. 11 and 12, the center line of the type guide is indicated by the vertical broken line. This line lies in a plane which passes through the longitudinal axes of the type bars when in printing position. In the present machine, the characters on the types are not centered with respect to the longitudinal axis of the type bars but are offset more to the right than to the left with reference to the center line in Figs. 11 and 12 as shown by the letter M in Fig. 12. One portion of all the characters is offset to the left (Fig. 12) a constant distance but the other portions of the letters are offset variable extents to the right of the center line depending upon the respective widths of the letters. For this reason, it is impractical to attempt to realign the carriage after inadvertently moving same or after making an erasure by centering one of the adjacent letters by means of the type guide as is usually the case in machines for general office work. The escapement mechanism is designed to space the letters so that the right hand portions of the letters always take a position a predetermined distance to the left of the center line which distance is slightly greater than the extent to which every letter is offset to the left.

In the preparation of typewritten master sheets for the photo-offset and other processes, it is highly desirable that the right hand margin of the typewritten matter be straight in order to have the printed sheets produced by the plates appear like printed matter printed from justified type. In order to facilitate the justification of the typewritten matter in the preparation of the master sheets, a justification indicator and signal device is provided. This device is shown in Figs. 1, 9, and 10. Mounted on the rear rail 28 near the right hand end thereof is a bracket 205 (Fig. 10) which slidably supports a rod 206. This rod has a short arm 207 secured thereto which is in the path of movement of the right hand marginal stop 103b whereby said marginal stop will engage the arm 207 as the carriage moves to the left in writing a line. The left hand end of the rod 206 is pivotally connected to one arm of a bell crank 208 (Fig. 9) on a stud 209 carried by an extension 102a formed in the plate 102. The other arm of the bell crank 208 has a link connection 210 with a lever 211 pivoted at 212 to a bracket 213 mounted

on the base 14. The other arm of the lever 211 has a link connection 214 to a slide 215 which is guided by a strip 216 secured to one side of a bar 217 mounted on the front cover plate 218 (Fig. 10). The slide 215 has its ends 215a formed with lugs which loosely extend around the edges of the strip 216 so as to guide the slide 215 for a longitudinal movement of the bar 217. One face of the bar 217 is inclined so as to be at right angles to the line of sight of a person using the machine and is graduated as shown in Fig. 9 to correspond with successive points .022" apart in the movement of the carriage. In other words, the spacing of the graduations on the bar 217 corresponds to the spacings which are given the carriage by the back space mechanism. The slide 215 has a portion 215b which extends over the surface of the bar 217 and is provided with an index line.

When the carriage in its movement reaches a position which is 31 units of spacing short of the right hand marginal position, the arm 207 (Fig. 10) will be engaged by the marginal stop 103b whereby with further movement of the carriage to the left, the rod 206 will be similarly moved, rocking the bell crank 208 in a clockwise direction (Fig. 9). This produces a corresponding movement of the lever 211, owing to the link connection 210, with the result that the slide 215, after the carriage has come within thirty-one units of spacing of the left hand margin, moves with the carriage and the pointer 215 will move the distance between two successive graduations for each unit of spacing of the carriage. When the slide 215 reaches the point 10 on the scale to the right of the zero position, that is, is ten units of spacing short of the marginal position, a lug 209a of insulating material mounted on the lever 208 operates the central member 219 of three contact elements insulatably mounted on a bracket 220 of insulating material carried by the rear rail 28 to cause all three of the contact members to make contact. This causes a buzzer, not shown, to operate to indicate that the carriage has come within ten spaces of the right hand marginal position and thereby warns the operator to take care to finish, if possible, the next word within the ten space zone between the right hand marginal position and the position in which the buzzer operates, or to split the word to avoid having the typewritten line extend beyond the right hand marginal position. It may sometimes be necessary to type beyond the marginal position and, because of this possibility, the scale on the bar 217 is continued for ten units to the left of the zero position in Fig. 9.

In order to produce a justified typewritten master sheet, it is desirable to first type the material in draft form on cheap paper taking care to terminate each line as close as possible to the right hand marginal position, that is, the zero position on the scale. As each line is completed in typing the draft, the operator notes the position of the index line with relation to the bar 217 and at the end of each line types the number of units the completed line is short of or beyond the zero or right-hand marginal position. The draft copy thus obtained is now re-typed on a sheet of high grade paper suitable for photo reproduction. Before retying each line, the operator first notes how many units of spacing the line is short of or beyond the right hand marginal position and then notes the number of words in the line. If the line includes numbers or letters standing alone, as well as words, the

operator counts the number of spaces between words.

As an illustration, it will be assumed that there are seven words in the first line and that the first line terminated six units short of the marginal position. This means that by inserting one additional unit of spacing between the words will cause the retyped line to become flush with the margin. This additional unit of spacing is inserted after each word by first operating the space bar twice which will cause the carriage to move eight units of spacing, remembering that the space bar causes the carriage to move four units of spacing when operated. The operator, after typing the first word, depresses the back space key three times which back spaces the carriage three units. The effect produced by these operations is to cause the first two words to be separated by five units of spacing. If these operations are repeated after each word of the first line, five units of spacing will likewise be produced between the remaining words. Thus, for the seven words of the first line, six additional spaces will have been inserted causing the first line to terminate at the right-hand margin. In other words, after the first line has been retyped, the slide 215 should occupy the zero position of bar 217. By similar manipulation of the space bar and back space key, the spacing between words may be varied by small increments to cause each line to terminate flush with the margin.

If, in the illustrative case, the line terminated beyond the marginal position, whereby the slide 35 215 indicates six units of spacing beyond the marginal position, it would be necessary to operate the space bar once after typing each word and then operate the back space key once whereby the words comprising the first line would be spaced apart three units of spacing instead of five. In the event that it is not possible to evenly space the words of a line to bring the line flush with the right hand margin, as for instance, in the event that the line terminated three units 40 of spacing short of the margin instead of six, the extra space produced by operating the space bar twice and then the back space key three times would be produced between only four of the words and the remaining words would receive the same spacing as in typing the first draft.

In some cases, it may be necessary to insert or remove one or two spaces between two words owing to the fact that some letters are considerably wider than other and even though the line may be nearly flush with the margin, the width of the last letter typed may cause the last word of the line to extend beyond the marginal position to such an extent as to be noticeable with reference to a preceding or following line which terminates flush with the margin. As an illustration, the lower case letter "l" is very considerably narrower than the lower case letter "m" and the difference is so great that if two successive lines terminated with the letters "l" and "m," respectively, the margin would be noticeably ragged in the justified copy owing to the letter "m" being offset to the right an extent sufficient to be noticeable. In this case in re-typing the first copy a unit may be subtracted between two words whereby the letter "m" will not, in the final draft, project beyond the marginal line so noticeably. While this procedure may not be absolutely necessary to produce a good appearing master sheet for production of a

printing plate, it will enhance the appearance of the final draft and make the sheets printed by the plate look more like they had been produced from justified type set by hand or from type produced by type casting machines such as the "Intertype" or "Linotype."

While there has been shown and described and pointed out the fundamental novel features of the invention as applied to a single embodiment it will be understood that various omissions and substitutions and changes in the form and details of the device illustrated and in its operation may be made by those skilled in the art without departing from the spirit of the invention. It is the intention, therefore, to be limited only as indicated by the scope of the following claims.

What is claimed is:

1. In a machine of the class described, the combination of a carriage, a plurality of escapement mechanisms, means interconnecting said escapement mechanisms whereby they may be operated singly or in combination to produce an accumulative effect on the carriage, typing means, power means to operate the typing means, a series of key levers for selectively controlling the operation of the typing means by the power means, selecting means operated by the power means concurrently with the operation of the typing means, means common to the escapement mechanisms for operating the escapement mechanisms, and normally ineffective means rendered effective by the selecting means for coupling the escapement mechanisms to the operating means combinationally.

2. In a machine of the class described, the combination of a carriage, a plurality of escapement ratchets, differential gearing interconnecting the escapement ratchets with each other and with the carriage; a plurality of dog rockers, one for each escapement ratchet; dogs on said rockers for controlling the rotation of the ratchets, a plurality of arms each mounted on one of the dog rockers, a common operating member, typing means, keys for controlling the typing means, and selecting means controlled by the keys for operatively engaging the arms with the common operating member combinationally.

3. In a machine of the class described, the combination of a carriage, typing means comprising a series of type bars, a continually operating power roller common to all the type bars, cam units each connected to a type bar and adapted to be selectively engaged with the power roller to operate the type bar, keys for selectively engaging the cam units with the power roller, a series of selector bars each associated with a key and having a connection to the corresponding cam unit whereby the selector bars are operated each time the corresponding cam unit is operated, a series of escapement mechanisms with means interconnecting said escapement mechanisms and said carriage, means common to the escapement mechanisms and normally disengaged therefrom for operating said escapement mechanisms, means individual to each escapement mechanism for coupling the escapement mechanisms to the operating means, and means for operating the coupling means in different combinations under control of the selector bars as determined by said keys.

4. In a machine of the class described, the combination with a carriage, multiple escapement mechanisms operative to feed the carriage variable extents, typing means, means to operate the

typing means, means to selectively control the operation of the typing means, means common to the multiple escapement mechanisms for operating said escapement mechanisms, a plurality of 5 normally ineffective interponents each associated with one of the escapement mechanisms and operable to connect said mechanisms to the common operating means, and selecting mechanism controlled by the first named selecting 10 means for operating the interponents combinationally.

5. In a machine of the class described, the combination with a carriage, a series of escapement ratchets, differential gearing interconnecting said ratchets and said carriage, a plurality of dog rockers each associated with one of said ratchets and having escapement dogs, typing means, keys for controlling the typing means, a universal bar operated by the typing means, a slide common to the dog rockers and having a connection to the universal bar whereby said slide is moved longitudinally each time a character is typed; interponents, each pivotally mounted on one of said rockers and movable into engagement with said slide; selector mechanism for moving said interponents into engagement with said slide for operation thereby, and power means controlled by said keys for operating the selector means each time the character is typed.

6. In combination, a carriage, type bars, means to variably space the carriage according to the widths of the characters typed including a plurality of selectable escapements, selecting means for combinationally selecting the escapements for operation, character keys, power means controlled by said keys for operating the selecting means and type bars, and means controlled by the selecting means and operated by the type 40 bars for operating the selected escapements.

7. In a machine of the class described, typing means, a carriage for a record sheet; selectively operable elements, each representing a character, for controlling the operation of the typing means, 45 each element when operated causing a character to be typed by the typing means; means controlled by said elements for operating the typing means; variable feed mechanism for the carriage including a series of feed controlling elements, each 50 being operable to cause a predetermined feed of the carriage, and operable singly or in various combinations to produce a plurality of different feeds of the carriage greater in number than the number of feed controlling elements; means connecting the feed mechanism to the carriage, a common operating member with which said feed 55

controlling elements are engageable, and means controlled by the selectively operable elements for engaging the feed controlling elements with the common operating member.

8. In a machine of the class described, typing means, a carriage for a record sheet, selectively operable members representing characters for controlling the operation of the typing means, each member when operated causing a character to be typed by the typing means; means controlled 10 by said members for operating the typing means; variable feed mechanism for the carriage including a series of feed controlling elements for the feed mechanism, each element being operable to cause a predetermined feed of the carriage and 15 operable either singly or in various combinations to produce a plurality of different feeds of the carriage greater in number than the number of operable elements; means connecting the feed mechanism to the carriage; means common to 20 said operable elements for operating one or more of said elements, said elements being selectively operatively engageable with the common operating means; and control means intermediate the selectively operable members and the feed controlling elements for selectively and combinationally engaging the latter with the common operating means whenever one of the selectively operable 25 members is actuated.

9. In a machine of the class described, typing means, a carriage for a record sheet; selectively operable elements for controlling the operation of the typing means, each element representing a character and, when operated, causing the typing means to print such character; means controlled by the selectively operable elements for operating the typing means; variable feed mechanism for the carriage including a series of feed controlling elements, each, when operated, causing the carriage to be fed a predetermined 30 amount, said feed controlling elements being normally idle and operable singly or in various combinations to cause the carriage to be fed a plurality of different extents; means to connect the feed mechanism to the carriage, means common to 35 said feed controlling elements for operating the latter to effect a feed of the carriage, a second operating means for rendering the feed controlling elements operable by the common operating means, and means controlled by the selectively operable elements for causing the last named operating means to operate the control elements 40 singly or in combination each time one of the selectively operable elements is actuated.

RONALD D. DODGE.
